UNITED STATES PATENT OFFICE

2,261,854

EXHAUST STEAM INJECTOR

Richard David Metcalfe and James Croxon Metcalfe, Romiley, England, assignors to Davies & Metcalfe Limited, Romiley, England, a British company

Application July 23, 1940, Serial No. 347,071

In Great Britain August 11, 1939

2 Claims. (Cl. 103—265)

This invention relates to exhaust steam injectors and is concerned with the supply of boiler or live steam which is throttled down to low pressure and serves to work the injector when exhaust steam is not available. Usually a nozzle or choke tube is provided between the branch containing boiler or live steam and the valve, called the automatic shuttle valve, which controls the flow of the throttled down live steam to take the place of exhaust steam when the engine which supplies the latter is not functioning.

In accordance with our present invention, we provide an automatic auxiliary choke which regulates the area for the flow of live steam to take the place of exhaust steam in accordance with the pressure of the live steam.

Referring to the accompanying explanatory drawings:

Figure 1 is a longitudinal section and Figure 2 a cross section on the line 2—2 of Figure 1 showing an exhaust steam injector having our invention applied thereto in one convenient form.

a indicates the inlet for exhaust steam, *b*, *b*¹ the double beat valve for controlling the inflow of the exhaust steam, *c* the supplementary live steam inlet nozzle, *d* the inlet for live steam throttled down to low pressure which is used to work the injector when exhaust steam is not available, and *e* the adjustable cone for controlling the inflow of water to the injector, the adjustment of such cone being effected by the spindle *f* having a crank pin *g* on its end which enters a hole in a bush *h* let into the cone *e*. The spindle *f* also turns the water cut off valve *i*. There are two further fixed cones *j* and *k* in advance of the combining nozzle *m* which has a hinged flap *n* therein, *o* is the delivery nozzle.

The live steam inlet branch to the injector is at *p* (Figure 2). Such steam can pass directly to the nozzle *c* and can pass by way of the choke tube *t* to the passage *r* and thence, under the control of the automatic valve *s*, to the space *d* before referred to.

The quantity of steam (known as the auxiliary steam) admitted to the chamber *d* is determined by the bore of the choke tube *t* and the boiler pressure.

To keep the auxiliary steam pressure approximately constant with fluctuating boiler pressure, the effective choke tube area should vary inversely with the boiler pressure.

The choke tube *t* and its internal spindle *q* constitute what we term an automatic auxiliary choke which gives an automatic adjustment of

the steam flow area from the branch *p*, to the passage *r* and space *d* varying with the pressure in branch *p* so that such area is reduced with increase in the pressure of the live steam pressure in *p* and vice versa. The spindle *q* with a conical or stepped end portion is fitted concentrically within the choke tube *t*. The enlarged end of the spindle *q* (which is within a chamber *x* in communication with chamber *r*) is guided by a stem *v* and is flanged to receive the end of a compression coil spring *w*.

There is a balancing action between the steam pressure in chamber *p* tending to push down the spindle *q* and the force of the spring *w* together with the steam pressure in the throat of the choke tube *t* which tend to push up the spindle *q*. The pressure in the throat of the choke tube *t* is always proportionately less than the steam pressure in chamber *p* due to the Venturi action at the throat of the tube. It will be seen therefore that there is always a balancing action between the live steam pressure acting to push down the spindle *q* and the reduced pressure at the throat of the tube *t* applied to the spindle *q* assisted by the pressure of the spring *w*. This results in an automatic adjustment movement of the spindle *q* with every change in live steam pressure and gives a reduction in flow area past the spindle through the tube *t* for an increase in live steam pressure and vice versa.

What we claim is:

1. In an exhaust steam injector, an automatic auxiliary choke which regulates the area for the flow of live steam to take the place of exhaust steam for working the injector when exhaust steam is not available, in accordance with the pressure of the live steam, said automatic auxiliary choke including a steam inlet tube and a spring controlled movable spindle fitted concentrically therein, said spindle having a diverging conical-like end at the inlet end of the choke tube, the larger end of said movable spindle projecting into a chamber open to the boiler pressure, said pressure tending to push down the conical or stepped end into the choke tube thereby reducing the steam inlet area, this movement being resisted by the proportionate balancing action of the spring and of the reduced pressure of the steam in the throat of the choke tube.

2. In an exhaust steam injector, an automatic auxiliary choke which regulates the area for the flow of live steam to take the place of exhaust steam for working the injector when exhaust steam is not available, in accordance with the pressure of the live steam, said automatic auxil-

iary choke including a steam inlet tube and a movable spindle fitted concentrically therein, said spindle having a diverging conical-like end at the inlet end of the choke tube, the larger end of said movable spindle projecting into a chamber open to the boiler pressure, said pressure tending to push down the conical or stepped end into the

choke tube thereby reducing the steam inlet area, this movement being resisted by the proportionate balancing action of the reduced pressure of the steam in the throat of the choke tube.
